UNITED STATES PATENT OFFICE.

IVAN RISDON, OF SEATTLE, WASHINGTON.

FURNACE.

1,315,158.

Specification of Letters Patent. Patented Sept. 2, 1919.

Application filed March 31, 1917. Serial No. 158,969.

To all whom it may concern:

Be it known that I, IVAN RISDON, a citizen of the United States, residing at Seattle, in the county of King and State of Washington, have invented certain new and useful Improvements in Furnaces, of which the following is a specification.

This invention relates to furnaces adapted to burn the cheaper grades of coal which is progressively fed into and through the furnace by mechanical stoking devices.

The object of the invention, generally stated, is to simplify and improve the construction of apparatus of this character to render the same more economical in the consumption of fuel, with a uniform fire at the different speeds at which the stoking and feeding appliances are actuated.

The invention consists in the novel construction, adaptation and combination of parts, as will be hereinafter described and claimed.

In the accompanying drawings, Figure 1 is a longitudinal vertical section through a boiler furnace and apparatus embodying my invention which is applied thereto. Fig. 2 is a horizontal section of Fig. 1. Fig. 3 is a transverse sectional view through 3—3 of Fig. 2 and illustrating parts which are not shown in the referred to view. Fig. 4 is a transverse sectional view through 4—4 of Fig. 2.

In the drawings, the reference numeral 5 designates the furnace of a boiler 6, said furnace being inclosed by side walls 7, a rear wall 8 and a front wall 9 having the usual or any suitable stoking and ash-pit openings, as at 10 and 11.

In carrying out my invention, I provide within the aforesaid furnace a supplementary furnace comprising a flaring tunnel member 12, grate members 13 and 14 and an apron member 15 arranged substantially as shown in Figs. 1 and 2.

Opening into the forward end of the tunnel member 12 is a tube 16 having its forward end closed by a plate 17 and, near the latter, communicating with the discharge end of a coal hopper 16¹.

18 represents a conveyer screw operating within the tube 16 and mounted upon a shaft 19 which may be driven at a slow speed by

any suitable means, such, for example, as by worm gearing 20 from a shaft 21 which, in turn, is driven through the agency of 55 spur gears 22 from the power shaft 23 of a motor 23¹.

This motor may also be utilized to operate, as by means of belt 24 and pulleys 25, a rotary fan or blower 26 for delivering air under pressure through pipe 27 and also, through a branch pipe 27¹ provided with a regulating valve 27², into the tube 16 between the outlet end of the latter and the discharge opening of the fuel hopper 16¹. 60 Said tunnel member is formed with double walls 12¹, 12² to afford an air chamber 28 which surrounds the inner wall 12¹, said chamber being connected from in front with the air supply pipe 27 and at the rear is 70 provided with small outlet holes 12², and communicates by openings 29, 29¹, respectively, with wing passages 30 and 30¹ provided at the outer sides of the sloping side walls 13¹ of the member 13. The openings 75 29, 29¹ are proportioned to furnish as near as practicable an equal quantity of air to each of the passages and within the latter are spaced fins 31 depending from the respective side walls 13¹ to better distribute 80 the air against the latter for cooling the same. The fins also serve as heat-conducting agents to transfer heat derived from the referred-to walls to the air in the passages. The air thus heated is delivered from near 85 the rear ends of said passages through holes such as 32¹ into a compartment 32 from whence it escapes through the grate holes to the bed of fuel for combustion purposes.

The member 13 is flanked by walls 33 of 90 brick or the like to which it may be rigidly secured, as by embedding the flanges 34 in the respective walls. These walls also serve to support pivots 14¹ and 15¹ of members 14 and 15 whereby they may be tilted, as by 95 means of links 35, 36 connecting arms 14² and 15² of the respective members with shaker levers 35¹, 36¹ provided in front of the furnace setting.

The grate members 14 and the apron 100 member have desirably plane upper surfaces. The grate members 14 are provided with apertures 14³ for the passage of air at natural draft to complete the combustion

when the fuel is being fed too rapidly to be entirely burned on said combustion member 13.

The upper surfaces of the grate members 5 and the fuel bearing surface within the tunnel 12 are, or may be, disposed in substantially a plane which inclines downwardly at a slight angle from the front to the rear. The apron, however, when in its normal position, as illustrated in Fig. 1, is inclined somewhat more than the others so as to afford an angle at α whereat clinkers or bodies of combustion products will usually break and slide down upon the apron into a conveyer trough 37 extending through a conduit 38 into a tight casing 39 within which are deposited the ashes received from the apron.

To effect such transfer of the ashes, I provide a chain conveyer 40 passing about live and dead sprocket wheels 41 and 42 carrying flights or blades 43 which serve to drag the ashes into the receiver casing 39 and also in traversing the outer edge 15⁴ of the apron 25 will coöperate therewith to shear off the clinkered mass which may be projected beyond the apron. The shearing effect of the various blades 43 is, moreover, facilitated by inclining them in the direction of travel. 30 The sprocket wheel 41 may be rotated to drive the chain in any convenient or suitable manner. As shown the shaft 41¹ of said pulley is operatively connected to the screw conveyer shaft by means of a chain 44 passing about sprocket wheels 44¹ and 19¹ on the respective shafts.

In operation, the coal supplied through the hopper 16¹ is delivered by means of the screw 18 through the tube 16 into the tunnel 40 12 wherein it is kept moderately cool by reason of the air-cooled tunnel wall 12¹.

The coal, while passing through said tunnel, spreads outwardly so that upon reaching the combustion grate member 13 it will 45 cover the entire width of the member between the side walls 13¹. The combustion occurs while the fuel is passing over the member 13 through which is fed the hot air from the chamber 32. The air in its travel 50 to the place of combustion passes around the inner wall 12¹ of the tunnel, thence through wing passages 30, 30¹ where the relatively cool air serves to lower the temperature of the walls 13¹ thereby preventing the fuel, 55 clinkers, etc., from adhering—as by fusing—to such walls, and enables the fuel bed to be propelled freely through the combustion chamber.

The unconsumed fuel, if any, with clinkered ash travels from the combustion member 13 over the members 14 through the apertures 14³ of which air under natural draft ascends to effect the complete burning of the fuel. The ash or ashes produced in 65 clinker form in being urged from behind

are likely to project for a distance over the edge α , Figs. 1 and 2, of the rearmost member until the weight of the unsupported part will cause it to break and fall upon the apron 15. From the latter it slides into the trough 70 to be broken and carried away by the conveyer blades.

The purpose of the branch pipe 27¹ is to conduit air into the tube 16 to afford pressure sufficient to create an air current in the 75 tube which will prevent the more volatile gases—which may be produced in the tunnel—from escaping through the hopper.

The above-described apparatus will operate with a clinkering coal, including nearly 80 all of the lignites, so that the screw can push, as it were, everything ahead to the trough. The coal will not clinker to any appreciable amount while being pushed through the air-cooled tunnel, but by being of considerable 85 depth will afford enough resistance to cause the clinkering and clinkered material to be shoved thereby.

In practice, the combustible portion of the fuel is usually consumed before it has 90 reached or passed but a short way over the members 14. The combustion member is at a high temperature, as is likewise the pre-heated air which is supplied therethrough into the fuel from below.

The ashes are intended to be carried away by the conveyer therefor and the only purpose of making the members 14 and the apron 15 of the rocking-grate type is to enable an attendant to shake them to break up the mass thereabove when it becomes unduly caked. The apron 15 is disposed considerably below the level of the member 13 above which the greater part of the combustion occurs, and is accordingly not subjected to much heat.

What I claim, is—

1. The combination with a furnace having a combustion chamber provided with an opening in its front wall, of a structure comprising a tunnel member provided with hollow walls extending through said opening, and a combustion member located within said combustion chamber, said combustion member comprising an apertured floor, an air 110 compartment therebelow and with hollow wing elements which extend to a higher elevation than the floor and affording imperforate side walls therefor, means to supply air under pressure through said tunnel 115 walls and the wing elements into said compartment, and means to feed fuel through said tunnel and longitudinally over said floor.

2. The combination with a furnace having 125 a combustion chamber provided with an opening in its front wall, of a structure comprising a tunnel member provided with hollow walls extending through said opening, and a combustion member located with- 130

in said combustion chamber, said combustion member comprising an apertured floor with hollow wing elements which extend to a higher elevation than the floor and afford-
5 ing imperforate side walls therefor, means to supply air under pressure through said tunnel walls and the wing elements to main-
tain the walls of the latter at a temperature

which will obviate the adhering thereto of
clinkers traveling in the fuel bed over said 10
floor, and means to effect the feeding of
fuel through said tunnel and the subsequent
movement of the fuel bed upon the floor.

Signed at Seattle, Washington, this 22nd
day of March, 1917.

IVAN RISDON.
